UNITED STATES PATENT OFFICE.

MERRILL B. PARKER, OF ROCKWOOD, TENNESSEE.

STOCK-DISTRIBUTER AND GAS-SEAL FOR METALLURGICAL FURNACES.

No. 883,044.

Specification of Letters Patent. Patented March 24, 1908.

Application filed March 30, 1906. Serial No. 308,951.

To all whom it may concern:

Be it known that I, MERRILL B. PARKER, a citizen of the United States, residing at Rockwood, in the county of Roane and State of Tennessee, have invented new and useful Improvements in Stock-Distributors and Gas-Seals for Metallurgical Furnaces, of which the following is a specification.

This invention relates to a stock distributor and gas seal for metallurgical furnaces, and the primary object of the same is to provide positively operating means for equally distributing the coarse and finer materials deposited into a feed hopper organization by a skip to avoid a deposit of all the fine material on one portion of the bell and the coarse material on another part of the latter, and also to produce a reliable gas seal to prevent the escape of the gases from the furnace when the bell is opened to admit the material into the furnace.

This stock distributor and gas seal is of the type illustrated by U. S. Letters Patent Nos. 737,519 and 737,520, dated February 17, 1903.

The improved distributor and seal consists of a distributor ring and four distributor doors. These doors are rectangular in shape and are hinged to the bottom of the distributor ring, and each door is operated independently and directly by means of a piston rod coöperating with a cylinder, each piston rod being attached to an intermediate portion of each door. Two of the doors in the improved distributor and seal are allowed to remain open and hang in vertical position, while the other two doors are closed, forming a V-shaped trough at the bottom of the receiving chamber in which is deposited a skip car-load of material, all of which will be more fully hereinafter set forth.

In the accompanying drawings, Figure 1 is a side elevation of a stock distributor and gas seal for metallurgical furnaces embodying the features of the invention and showing in conjunction therewith skip car operating means. Fig. 2 is a top plan view of a portion of the distributor mechanism particularly illustrating the features of the invention. Fig. 3 is a side elevation of the mechanism illustrated by Fig. 2, and partially broken away, a part of the doors or gates being shown in closed position. Fig. 4 is a transverse section through the ring and doors or gates showing the piston rods broken away and attached to a part of the gates. Fig. 5

is a sectional elevation of one of the cylinders and piston rods for one of the doors.

Similar characters of reference are employed to indicate corresponding parts in the several views.

All of the parts of the apparatus shown, except those which will be more fully herein-after set forth, are similar to the construction disclosed by the patents hereinbefore mentioned, and the specific improvements in the present instance are confined to the doors arranged immediately under the receiving hopper and above the cone or bell, which are devices well known in the art.

The skip car A shown in the drawings is elevated over the inclined track B by the mechanism shown, and when it reaches a certain point is caused to dump inwardly and deposit its contents into the receiving hopper 1, which, in the present instance, is elliptical in form and so arranged that the longer axis thereof will be directly under the outlet end of the skip car, so as to catch all of the load. The receiving hopper 1 has a bottom outlet opening 2 of circular form, and directly under the said opening, and in close relation thereto, a door or gate supporting ring 3 is disposed and has a downwardly directed inclined chute or supplemental hopper 4, with an enlarged bottom opening 5. The center of the opening 5 is disposed in vertical alinement with relation to the apex of the cone or bell 6, which is lowered and raised, or moved vertically in reverse directions to open and close the inlet aperture or mouth of the furnace 7. The depending auxiliary chute 4 of the ring 3 is inclosed by a conical sheathing 8, which extends downwardly to the top of the furnace around the inlet aperture or mouth of the latter. The auxiliary hopper or chute 4 is practically in the form of an inverted quadrangular, truncated pyramid, and projecting downwardly from the center of the sides thereof are pairs of ears 9, to which corresponding ears 10 projecting above the upper edges of rectangular doors or gates 11 are pivotally connected, so that the doors or gates will be free to swing inwardly and outwardly. These doors or gates 11 have their lower edges beveled outwardly and downwardly, as at 12, to permit the same to closely fit against each other when moved inwardly, and at the center of the lower edge of each door is a slot 13 to receive the bell operating rod 14.

At the center of the outer side of each door

or gate 11 and nearer the upper edge of the latter, are a pair of coupling bosses or ears 15, and movably attached to each door through the medium of the ears or bosses 15 is a piston rod 16, which is rigid throughout its entire length and actuated by a suitable piston 17, shown in dotted lines by Fig. 3, and disposed in a cylinder 18 supported on a pillar 19. Each piston 17 is engaged by a spring 20, which has the function to return the piston to normal position when released, or when the fluid pressure operating medium is liberated or withdrawn therefrom. The cylinders 18 with the pistons 17 therein and the piston rods 16, coöperate with each door or gate 11, and have a positive or direct action with respect to the latter, without the least lost motion, and with increased power in view of the fact that the piston rods 16 are rigid throughout their entire lengths, and are attached to the doors or gates at the points specified to insure a quick responsive action of the said doors or gates in the closing and opening movements of the latter.

The doors or gates, as will be understood, are arranged in opposing pairs, one pair of these doors or gates being closed or moved inwardly to first form a V-shaped trough, as clearly shown by Fig. 3, and subsequently the doors first forming the V-shaped trough are opened and the remaining pair of doors or gates are moved to occupy a similar position, and this operation is continued in alternation as long as may be desired, or until the charge of material for the furnaces has been fully deposited in the receiving hopper and properly distributed or disposed around the bell. In charging the furnace, while two of the doors are moved inwardly and form the V-shaped trough, a skip car-load of material is deposited in the receiving hopper, and one of the doors or gates is moved to open position, and thus the bottom of the V-shaped trough, as formed by the remaining inwardly projected door or gate, becomes a sloping spout, and the remaining doors or gates hanging in vertical position provide end closures, and by this means the material striking the door or gate projected inwardly at an angle is diverted and thrown against the opposing door or gate and thus causes the equal distribution of the coarse and finer material embodied in the stock around one portion of the bell. The door or gate of the pair of doors which, as just explained, was opened, to provide a diverting means for its opposing inwardly projecting inclined door or gate, is then of itself projected inwardly and the companion door or gate is opened and caused to assume a vertical position to also become a diverting means for the stock coming through the receiving hopper. The remaining doors or gates which have hung in vertical position and provided end closures for the doors or gates which have been oper-

ated, are then similarly actuated and alternately projected inwardly in inclined position and drawn outwardly into open or vertical position. By this means, the stock will be regularly deposited around the bell with the coarse and finer material equally disposed with respect to the bell. It is unnecessary to operate any particular pair of doors or gates, as either pair may be actuated, as just set forth, and made to form a chute or spout in any one of four directions. Furthermore, two of the doors may be closed, and with the addition of the remaining doors in vertical position at the ends of the closed doors, a gas seal is produced which prevents furnace gases from escaping when the bell is arranged to admit the material into the furnaces.

The cylinders 18 are adapted to be charged with steam or other fluid pressure, and are preferably single acting, the weight of each door being such that when the fluid pressure is released from the corresponding cylinder the piston in the latter will be forced outwardly into normal position, and such movement of the piston is facilitated by the use of the release spring 20. The pressure, whether steam or other kind, is supplied to the cylinders by pipes 21, which are brought into close relation and projected from one side of the apparatus, as at 22, and connected in pairs to controlling valves 23, conveniently located, or within easy reaching distance of the skip car operator. By throwing either one of the valves 23 into open position, two of the cylinders 18 will be charged and operate as heretofore explained. It will be understood, however, that these controlling valves will be so constructed that one cylinder of each pair may be relieved of its pressure medium before the other to arrive at the operation of first opening one door or gate of each pair to serve as a diverting means for the companion door or gate which may be projected inwardly at an angle of inclination.

The arrangement of the doors or gates and the operating mechanism, as stated, provides for distributing the stock material in four directions without depending upon the apex of the bell to so distribute the material. It is also possible with the apparatus, as explained, to divert all of the material in one direction, or a part only in a certain direction and a portion in another. Through the medium of the change of operation of the doors, which can be quickly accomplished by the actuation of the controlling valves 23, a number of combinations of distribution can be made, if it is found advisable.

Fig. 5 shows the preferred form of cylinder and piston rod used in connection with the doors, and it will be seen that the rigidity of the piston rod throughout the entire length of the latter is preserved by permitting the

same to have a slight movement in the cylinder to compensate for the arcuate motion of the door. The cylinder construction shown by Fig. 5 does not form a part of this invention and is well known in other arts, the essential feature of the invention being the piston rod formed without joint or break between the cylinder and the door and movably attached to the intermediate portion of the said door so as to be direct-acting and provide the door with sensitively operating means to quickly open and close the door without the least lost motion and without having to use power other than that required for opening and closing the door and in contradistinction to those structures heretofore used, wherein the connections between the doors and the power mediums were indirect or loose and in some instances where the weight of the door as an entirety had to be overcome in the opening and closing movements, and especially the opening movements by reason of the engagement with such doors of the connections at points distant from the intermediate or central portions thereof.

Having thus fully described the invention, what is claimed, is:

1. In a stock distributor and gas seal of the class specified, the combination with a receiving hopper and a furnace having a bell, of opposing pairs of doors hinged at their upper extremities to the lower portion of the hopper above the bell; and mechanism operating with the doors for either simultaneously moving the opposing pairs of doors inwardly at an angle of inclination, or opening one door of the pair and permitting the other to remain in inwardly inclined position, and also for alternately similarly actuating the opposing pairs of doors, the said mechanism including radially disposed straight piston rods rigid throughout their entire lengths, each piston rod being movably and directly

attached to the outer side of one door below the upper hinged extremity of the latter, and fixed cylinders in alignment with the centers of the outer portions of the doors and having pistons therein to which the said piston rods are individually connected.

2. In an apparatus of the class specified, the combination with a receiving hopper and furnace bell, of pairs of doors movably held above the bell and disposed opposite to each other, the doors being hinged to and depending from the lower portion of the hopper, longitudinally straight piston rods rigid throughout their lengths and directly connected to the outer portions of the doors below the hinge connections for the latter, stationary cylinders having pistons therein to which the piston rods are connected, the cylinders being individually disposed in alignment with the points of attachment of the piston rods to the doors so that one cylinder and one piston rod coöperate with each door, and fluid pressure conveying means connected to the cylinders for operating each pair of doors to project the latter simultaneously inward in pairs at opposing angles of inclination or to open one door and permit the other of the opposing doors to remain at an inward angle of inclination and to simultaneously operate each pair of doors in a similar manner while the remaining doors are inactive and serve as end closing means for the active doors, the fluid pressure conveying means emanating from one portion of the apparatus and provided with separate controlling valves to render each pair of doors independently operative.

In testimony whereof I have hereunto set my hand in presence of two subscribing witnesses.

MERRILL B. PARKER.
